[57] CLAIM

The ornamental design for a fishing line holder, as shown and described.

DESCRIPTION

FIG. 1 is a top plan view of a fishing line holder showing my new design;

FIG. 2 is a side elevation of the new fishing line holder of my design;

FIG. 3 is a bottom plan view thereof; and

FIG. 4 is a vertical cross section taken on the lines 4—4 of FIG. 1, it being understood that said cross section shows in greater detail certain of the aspects of my new design, and in particular, surface contours which are more clearly apparent in cross section.
